REFRACTORY BRICK CONSTRUCTION

Jay B. Tracy, Upper Darby, Pa., assignor to General Refractories Company, Philadelphia, Pa., a corporation of Pennsylvania

Application August 25, 1937, Serial No. 160,843

1 Claim. (Cl. 122—156)

Domestic boilers of the vertical type comprise a shell mounted upon a flat base and a water leg spaced above the flat face of the base, and when adapted for use with liquid fuel burners the combustion chamber is generally circular or curvilinear in plan. The combustion chamber is bounded by a refractory wall which must protect the lower part of the water leg from undue heat and which is backed up by a filling of refractory material confined within the shell. The installation of the refractory lining and the assurance of its proper performance present difficulties, among which the following may be referred to, the lining must be inserted and installed through the door with which the shell is provided and which does not afford much room for the purpose; the lining must extend above the lower portion of the water leg in order to protect the wall of the water leg if mud or sediment should collect in the water leg; the lining must be capable of conforming to the required cross section of the combustion chamber and therefore its units must be capable of being individually positioned and supported at any point on the face of the base, and the units should be duplicates; the lining should be as free as possible from joints and the necessary joints should be such as are readily sealed by the packing of heat insulating material which surrounds the lining.

The objects of the present invention are first, to provide a comparatively inexpensive structure by which the combination as a whole is improved, simplified and made more efficient in respect to both construction and mode of operation; and second, to provide a refractory brick which by reason of its form and provisions is especially useful as an element of the complete combination or structure, and which is adapted to impart to the complete combination or structure, as a whole, improved results.

Generally stated the invention comprises substantially rectangular refractory bricks having flat ends which adapt them to be stood in any required position and location upon the flat face of the base in conformity with the outline of the combustion chamber, and of which the length exceeds three times the width, whereby the bricks in a single course extend from the base above the bottom of the water leg to protect it from overheating and the sides of the brick having interengaging curved tongue and groove elements struck from the centre line of the brick on substantially the same radius, and the substantially flat and parallel faces of the brick providing respectively a bearing on the outside for the heat

insulating packing, and on the inside a smooth wall defining the combustion chamber.

The invention also comprises the improvements to be presently described and finally claimed.

In the following description reference will be made to the accompanying drawing forming part hereof and in which,

Figure 1 is a vertical sectional view illustrating features of the invention.

Fig. 2 is a top or plan view of Fig. 1 with parts 10 omitted, and

Figs. 3 and 4 are end views respectively illustrating modifications.

Referring to the drawing, there is shown a domestic boiler of the vertical type and it includes 15 a base having a flat face 1, a shell 2 and a water leg 3 with a sediment space 4 at the lower portion of the water leg, the sediment space 4 is spaced above the flat face 1. There is a combustion chamber and it is of generally curvilinear cross 20 section, as shown it is substantially circular but it is frequently oblong with straight sides and curved ends, the latter form is not shown because it is too well understood to require illustration or further description. The refractory bricks 5 25 have substantially flat faces and curved tongue and groove edges of substantially the same radius and struck from a center at substantially the median line of the brick, in this way the bricks may conform to the cross section of the combustion chamber. The bricks extend from the flat face 1 of the base to a point above the sediment space 4 so that they serve to protect the latter from overheating. The bricks have flat ends 6 30 of which one conforms to and rests on the flat face 1 of the base and of which the other is adapted to resist combustion at and near the sediment space 4. 7 indicates insulating material interposed between the shell 2 and the bricks and it is adapted to stop or pack the tongue and groove 35 joints, the substantially flat and parallel faces of the brick provide respectively a bearing for the packing material 7 and a smooth wall for the combustion chamber, the flat ends of the bricks enable them to be placed in any position on the flat face 1 so as to conform with the contour of the combustion chamber which may be either 40 circular or somewhat oblong.

The faces of the brick have been referred to as flat and generally parallel, however, one of them 50 may be flat and the other arcuate or curved as in Fig. 2, or both of them may be arcuate or curved as in Fig. 3, or both of them may be flat and straight as in Fig. 4. 8 indicates liquid fuel burning equipment.

By way of further description it may be said that the width of the brick may be from four to nine inches and the thickness of it approximately from one to three inches and these dimensions are standard with bricks. However, the brick is descriptively from fourteen to twenty-four inches long which is an unusual dimension and its purpose is to have the brick extend, when stood on its flat end on the flat face of the base sufficiently far above the bottom of the water leg to protect it from fusion and disintegration by burning.

10 I claim:

15 For use with a liquid fuel burner and a domestic boiler of the vertical type having a flat base and a shell and a water leg with a sediment space at the bottom thereof and spaced from and above the flat base and having a combustion chamber of generally curvilinear outline, the combination

with the shell and flat base of refractory bricks each having parallel faces and curved tongue and grooved edges of substantially the same radius and struck from a center at substantially the median line of the brick whereby the bricks conform to the cross section of the combustion chamber, said bricks each individually extending from the flat face of the base to a point above the sediment space and having flat ends of which one conforms to and rests on the flat face of the 10 base and of which the other is adapted to resist the combustion at and near the sediment space, and insulating material interposed between the water leg and the flat end of the bricks and adapted to stop or pack the tongue and groove 15 joints.

JAY B. TRACY.
